UNITED STATES PATENT OFFICE.

ARTHUR W. WALKER, OF MALDEN, MASSACHUSETTS, ASSIGNOR TO WALKER AND PRATT MANUFACTURING COMPANY, OF BOSTON, MASSACHUSETTS, A CORPORATION OF MASSACHUSETTS.

GAS-STOVE, (MANIFOLD.)

1,222,824.

Specification of Letters Patent. Patented Apr. 17, 1917.

Application filed January 26, 1914. Serial No. 814,314.

To all whom it may concern:

Be it known that I, ARTHUR W. WALKER, a citizen of the United States, residing at Malden, in the county of Middlesex and 5 State of Massachusetts, have invented new and useful Improvements in Gas-Stoves, (Manifold,), of which the following is a specification.

This invention relates to gas stoves. More 10 particularly it relates to improvements in means for introducing the gas and conveying it to the burners. Heretofore it has been customary to run a gas pipe called a manifold along the outside of the stove and to install short pipes with cocks, each leading thence to a burner. It is among the objects of the present invention to provide for the performance of the functions of the manifold, but to reduce the cost of production, 15 by eliminating elements and labor that have heretofore been thought necessary; to reduce the space required for a stove of given capacity; and to make improvements of design possible. These objects are accomplished by 20 forming a longitudinal chamber in the cornice of the stove top, running along over the burners, or by otherwise suitably modifying this arrangement so that a chamber is formed integral with the stove walls, to 25 which gas is admitted under its full pressure in normal and unmixed condition, and from which cocks lead to the several burners. Incidentally this provides other advantages, among which may be mentioned some 30 heating of the gas before burning; the saving of friction of gas in pipes and bends, making it possible to get a larger output of heat from a stove of given size when working under a given pressure in the gas mains; 35 and a stronger attachment for the cocks, because of the greater thickness of metal thus obtained for holding their screw threads. One embodiment of the invention is illustrated in the accompanying drawings, but 40 the invention may be embodied in other forms. It is the purpose of the patent to cover in the appended claim whatever features of patentable novelty exist in the invention disclosed.

50 In the accompanying drawings:

Figure 1 is a perspective view of the top of a gas stove embodying the invention with parts broken away;

Fig. 2 is a perspective view of another portion of a stove embodying the invention 55 in a different way, being a fragmentary view; and

Fig. 3 is a fragmentary view of a detail embodying the invention in still a different way.

Referring to the drawings, 10 represents the top of a gas stove having burners 11 of any ordinary or suitable type, the burners having pipes or mixing chambers 12 into which gas cocks 13 discharge. Air 65 may enter through spaces 14 to mix with the gas while passing through the pipes 12 in the ordinary way. In the embodiment of the invention represented in Fig. 1 the stove top has a cornice 15 which, unlike the usual 70 cornice, shelters the gas supply by the provision of an under wall 16 and a rear wall 17, thus making the chamber 18 which extends longitudinally along the row of pipes or mixing chambers 12 that lead to the burners. The walls of this chamber 18 are integral parts of the top of the stove, the chamber being formed by coring the mold in which the stove top is cast. As a result 75 there is absolutely no joint or possibility of 80 leakage of gas from the interior of this chamber. Holes are then drilled into the chamber at whatever locations are desired or convenient for the introduction of a pipe 19 for the inlet of gas and for the introduction of the cocks 13 to lead the gas outward 85 to the burners. This very simple description substantially comprises all that is necessary for an understanding of the invention. It 90 may be observed, however, that the bottom 95 wall 16 may be easily made as thick as desired to engage a number of threads and so to make a perfectly tight connection of the screw-cocks 13 and of the supply pipe 19. It is also to be noticed that the formation of the walls of this chamber integrally with the stove top facilitates the conduction 100 of heat from the other parts of the stove top to the walls which confine the gas, so that after the stove has been running a time the gas will become somewhat heated; also 105 that the straight, large and unobstructed character of the interior of the chamber 18, as compared with manifolds that have previously been used for supplying gas burners, allows such a free flow of gas when all burn-

ers are in operation that the most remote may get an adequate supply of gas with undiminished pressure.

The apparent elimination of anything in the nature of a manifold, which has been a visible characteristic of every gas stove heretofore known to me, is made possible by the construction described, is useful in that it materially simplifies the operation of cleaning the stove and makes possible a new range of designs of gas stoves. The elimination of this manifold, which ordinarily heretofore has been on the extreme outside of the stove, and so has been in danger from such shocks and blows incurred in transportation or when set up, also introduces an element of safety. As compared with those cases in which the manifold is a part of the piping system supplied by a local gas fitter who sets up the stove for use it is manifest that the labor of setting up is considerably reduced, because no connections need be made to the stove as shipped from the factory except to let the supply pipe 19 into the manifold; and it may be easily arranged by the maker so that this can be done at either end of the manifold, by providing a hole at each end and a plug for the one that is not used. The saving of space which results from the reduction of the outside dimensions may also be at times a matter of considerable importance, especially in houses of modern construction where kitchens and kitchenettes are made very small and two or three inches of additional space may permit the installation of a stove, or of some other apparatus beside the stove, which could not otherwise be accommodated.

While the drawings illustrate what I regard as the best form of the invention, it is possible to obtain some of the advantages of the invention even though the

chamber which constitutes the manifold be not integral with the stove top, but be formed in a separate piece of metal installed within the protection of the cornice. Such a modification is illustrated in Fig. 3, where the chamber 18 has walls 16' that are separate from the metal of the stove top, although in close proximity thereto under the cornice and protected thereby. If this chamber be made of cast metal it can be made to fit the shape of the underside of the cornice very much as if it were integral therewith, but in any event it eliminates the lateral exterior projection that has characterized gas stoves hitherto, and it can be tapped for supply and discharge of gases like the form shown in Fig. 1.

A modified way of applying the invention is illustrated in Fig. 2 which shows the oven burners, in a lower part of the stove. In this case a manifold, gas-tight chamber 18' is arranged with walls 16'' which are cast integral with the side walls 25 of the stove but are wholly concealed from external view, are protected from external dangers, and have the other benefits of the form of Fig. 1.

I claim as my invention:

In a stove, the combination of a supporting frame at the top of the stove comprising rails surrounding a burner opening, one of the rails having a cored gas supply passage therein; and a burner under the burner opening having one end supported by the cored rail and connected with the passage therein.

Signed by me at Boston, Mass., this 20th day of January, 1914.

ARTHUR W. WALKER.
